(57) **CLAIM**

An ornamental design for a female hose coupling, as shown and described.

DESCRIPTION

FIG. 1 is a front perspective view of a female hose coupling; FIG. 2 is a side view of the female hose coupling; FIG. 3 is a front view of the female hose coupling; FIG. 4 is a rear view of the female hose coupling; and FIG. 5 is a rear perspective view of the female hose coupling; and,

FIG. 6 is a partial cross-sectional view taken along line 6-6 of FIG. 2.

The broken lines in the drawings depict portions of the female hose coupling that form no part of the claimed design.
